[57] CLAIM

The ornamental design for a vegetable peeler, as shown.

DESCRIPTION

FIG. 1 is a top, left side, front perspective view of a vegetable peeler showing my new design, the peeler portion shown in broken lines for illustrative purposes only and forming no part of the claimed design;
FIG. 2 is a top plan view thereof;
FIG. 3 is a bottom plan view thereof;
FIG. 4 is left side view of FIG. 1;
FIG. 5 is a right side view of FIG. 1;
FIG. 6 is a front view thereof;
FIG. 7 is a rear view thereof;
FIG. 8 is a cross-section view on line 8—8 in FIG. 2;
and,
FIG. 9 is a cross-section view on line 9—9 in FIG. 2.

FIG. 2

FIG. 3

FIG. 4

FIG. 5

FIG. 6

FIG. 7

FIG. 8

FIG. 9
